AUTOMATIC ELECTRIC SERVICE LINE PRO-
TECTORJoseph E. Farrell, Washington, D. C., assignor to
Automotive Devices Corporation, Washington,
D. C., a corporation of Delaware

Application April 3, 1936, Serial No. 72,636

8 Claims. (Cl. 200—88)

The present invention relates to a device which will automatically function upon the occurrence of a short or overload in an electric service line to protect electric devices connected in the circuit 5 against damage.

A primary object of the invention is to provide novel improvements in a device of the electro-magnetic type wherein an electro-magnet becomes energized upon occurrence of the unusual condition 10 in the line thereby automatically and instantaneously to release means for opening and breaking the circuit.

Another object of the invention is to provide an electro-magnetic circuit breaker which includes a 15 fusible link set to operate at higher amperage than that at which the electro-magnet will function, and therefore the link will only melt under unusual load. For example if the electro-magnet will function at 10 amperes, the fuse selected will 20 not blow unless the load reaches or exceeds 15 amperes. In actual practice, however, it has been found that the electro-magnetic means always functions so quickly that the fuse seldom if ever is called into play, but nevertheless, it is provided 25 as an added or emergency safeguard. Accordingly, the invention provides a combined electro-magnetic and fusible link type circuit protector wherein the fusible link provides an additional factor of safety and will only become ruptured or 30 broken in the event that extraordinary conditions occur in the line.

A further object of the invention is to provide a screw-plug type construction adapted to fit in any screw shell receptacle and which has a minimum 35 length along its axis thereby permitting of its use in any standard fuse box, fuse panel or other equipment without adjustment or modification thereof.

A still further object of the invention is to provide 40 a novel cover for housing a spring tensioned disk or switch block, said cover having ratchet elements cooperating with spring brush terminals which function as pawls, said ratchet elements being a part of insulation barriers adapted to be interposed between the brush terminal elements and the contacts of the switch block so that in event the undesirable condition persists in the line, no damage or further shorting will occur after the 45 device has once functioned.

With the above and other objects in view, which will more readily appear as the nature of the invention is better understood, the same consists in the novel features of construction, combination 50 and arrangement of parts hereinafter more fully

described, illustrated in the accompanying drawings and defined in the appended claims.

A preferred and practical embodiment of the invention is shown in the accompanying drawings, in which:—

Figure 1 is a side elevation of the improved device.

Figure 2 is a top plan view thereof.

Figure 3 is a vertical cross-sectional view.

Figure 4 is a horizontal cross section taken on the line 4—4 of Figure 3.

Figure 5 is a top plan view of the plug base.

Figure 6 is a bottom plan view of the cap.

Figure 7 is a diagrammatic view showing the position of the disk-like switch block and barrier 15 walls carried by the cover when the device is set in the "on" position.

Figure 8 is a view similar to Figure 7 showing the relative position of parts when the current is "off".

Figure 9 is a side elevation of the cover showing 20 more clearly how the barrier walls are cut away to limit the movement of the disk relative to the cover.

Figure 10 is a perspective view of the disk or 25 switch block.

Similar reference characters indicate corresponding parts throughout the several figures of the drawings.

According to the embodiment shown in the 30 drawings the invention includes in its organization a plug body or base A and a cap structure designated generally as B. The plug body and the cap may each be completed before assembly so that the mere placing of them together brings them 35 into operative relationship. Any suitable means may be employed for holding the cap and base together, such for example, as the ring C or its equivalent.

Referring to the body or plug base A it may be 40 pointed out that the lower portion is surrounded by an external metallic screw shell connector 1, while the interior thereof houses an electro-magnet 2. The outer end of the core 3 of the magnet constitutes the center connector 4 of the device, 45 while the upper end is exposed in the bottom of a recess formed in the upper part of the base. The winding of the electro-magnet has one end 2^a connected to the core while the end 2^b is connected to an upstanding spring brush terminal 5, also 50 housed within the recess formed in the base. Another spring brush terminal 6 is located in the recessed base opposite the contact 5 and is electrically connected as at 6^a with the screw shell 1. The spring brush terminals 5 and 6 are preferably 55

made of spring conducting material and are each formed at their free ends with an inwardly offset contact portion *a* which also functions as a pawl as will later appear.

5 Between the contacts 5 and 6, and within the recessed upper portion of the base A there is also provided a spring-biased armature 7. This armature is preferably in the form of a plate pivotally supported at 8 and normally thrust away 10 from the upper end of the core of the electro-magnet by a spring 9. The forward or front end of the armature member 7 is provided with an upstanding detent or lug 10.

The inner side of the cover 11 is preferably 15 formed with a central post 15 and is also provided with the pendant barrier members or walls 16 and 17. As will be observed from Figures 3 and 4 these walls are located inwardly of the inner periphery of the flange or skirt 11^a thereby to 20 provide a space or channel for receiving the upstanding spring brush terminals 5 and 6. Also these walls are tapered or beveled at their front or toe ends as indicated in 16^a and 17^a, while the rear ends or heels 16^b and 17^b respectively are 25 squared or shouldered to provide in effect, ratchet abutments to cooperate with the ends *b* of the spring brush terminals as will presently appear.

The barrier walls 16 and 17 are also spaced 30 apart to provide a gap therebetween to permit of the offset portions *a* of the spring brush terminals 5 and 6 engaging with the contacts 18 and 19 carried by an insulating disk or switch block 20. The contacts 18 and 19 are connected 35 or bridged by a fuse link 21 embedded in a suitable groove or channel in the face of the said disk lying adjacent the inside face of the cover 11.

The disk or switch block 20 is preferably 40 chambered at one side as indicated at 21 to fit over the post 15, the diameter of the chamber 21 being sufficient to house and conceal a coil spring 22, one end of which is anchored in the post 15 of the cover, while the opposite end is 45 anchored to the disk within the chamber 21. Prior to assembling the disk 20 on the post it is preferred to place a sheath 23 of mica or its equivalent between the disk or switch block and the inside face of the cover, said sheath serving 50 as a transparent window for the openings 13 and 14 in the cover. For the purpose of holding the disk or contact block 20 to the cover any suitable detachable fastening may be used such, for example, as the screw 24. Thus, the disk or contact block may be readily renewed if desired.

The disk or block 20 is, of course, made of insulating material and snugly fits within the annular space provided between the curved barrier walls 16 and 17. Therefore, the disk is not only 55 supported for arcuate or oscillatory movement relative to the cover by the screw 24, but is also guided in its movement by the walls 16 and 17. The lower face of the disk 20 is provided with diametrically disposed offset lugs 25 and 26 and 60 is also provided with a laterally or radially offset arm 27 adapted to move between shoulders 28 and 29 formed by cutting away the bottom edges of the walls 16 and 17, thus limiting the relative movement between the disk and the cover 70 under the tension of the spring 22.

When the device is assembled as shown in Figure 3 it is ready for insertion into any screw shell receptacle. The face of the disk lying next to the cap, and shielded by the mica disk 23, is 75 preferably provided at spaced points with the

designations "On" and "Off" which will successively appear beneath the window 13. The fuse link or conductor 21 may be observed through the window 14.

In the normal service condition of the parts the armature 7 is urged upwardly by the spring 9, so that the lug 10 thereof is in engagement with one of the lugs, 25, for example, on the bottom of the disk 20 thereby placing the spring under tension. The cover 11 is prevented from 10 retrograde or backward movement by the ends *b* of the terminal brushes engaging with the ratchet shoulders 16^b and 17^b, of the barrier walls 16 and 17 respectively. (See Figure 7.) Thus the contacts 18 and 19 of the disk or switch block 15 are maintained in engagement with the portions *a* of the spring brush terminals 5 and 6. With the parts in this condition the circuit may be maintained in the line through the center contact 4; the winding of the electro-magnet; brush 20 terminal 5; contact 18; fuse 21; contact 19; and brush terminal 6 to the screw shell 1.

Upon the occurrence of a short or overload in the line, the switch is tripped in the following way:—The electro-magnet becomes energized 25 and attracts the armature type latch 7 against the tension of the spring 9 thereby drawing detent 10 of the latch out of engagement with the lug 25 of the switch or contact disk with which it has been engaged. Immediately upon 10 and 30 25 being separated, the tensioned spring will cause switch disk 20 to move forward and take contacts 18 and 19 away from the free ends of the springs constituting the line terminals 5 and 6, placing them behind the insulating barrier 35 walls 16 and 17. Simultaneously, the radial arm or projection 27 on the switch disk leaves the shoulder 28 on the insulating wall 17 and moves toward the shoulder 29 of the wall 16 (Figures 7 and 8). The effect of 27 striking shoulder 29 is 40 to push or move the cover 11 forward so that the ultimate position of parts after the electro-magnet has functioned is that shown in Figure 8. That is to say, when the radial arm or projection 27 of the switch disk strikes the shoulder 29 45 it will move the entire cover carrying the insulating walls 16 and 17 so that the bevelled toe portions of the walls will press the free ends of terminal springs 5 and 6 outwardly, thereby to be ready for the next snap engagement of the 50 springs with the contacts 18 and 19 upon the resetting of the device.

As will be apparent by comparison of Figures 7 and 8, the lug 25 on the exposed face of the switch disk moves substantially from the position 55 shown in Figure 7 to that shown in Figure 8 when the electro-magnet causes the release of parts 10 and 25. Therefore, the lug 26 will be the next lug to engage the detent 10 of the armature type latch 7.

Assuming that the device has been tripped, that is it has functioned to break the circuit by the action of the electro-magnet pulling the armature type latch 7 downwardly so that detent 10 moves out of the path of lug 25, it will, of course, be understood that if the short or other condition in the line has been removed, the device may then be reset by rotating the cover 11. In resetting, the initial movement of the cover is idle in the sense that the cover and the insulation walls 16 70 and 17 carried therewith may move a certain distance before the lug 26 in the switch disk again engages the detent 10 of the latch. The detent 10 of the latch is, of course, in its upper 75 position due to the deenergization of the electro-

magnet and, therefore, lies in the path of the on-coming lug 26. When 26 engages with 10, the turning of the cover winds the spring 22 and the switch disk and the cover are again tensioned. When radial arm 27 engages with the shoulder 28, the ends 16^b and 17^b of the members 16 and 17 release the free ends of the terminal springs 5 and 6 causing them to snap into the clearances provided between each insulating barrier wall 16 and 17, thereby to engage again with contacts 18 and 19 which, meanwhile, have been brought into position to be exposed through said clearances. Therefore, the various parts again assume the normal relation shown in Figure 7. 15 From this figure it will be apparent that the mutually tensioned switch disk and cover are respectively held in their locked positions by the lug 26 on the switch disk engaging with the detent 10 of the latch and because the free ends 20 of the terminal springs 5 and 6 engage behind the ratchet shoulders 16^b and 17^b of the insulation barrier walls.

In the event that the short or overload persists in the line, it will be impossible to reset the device because immediately upon terminal springs 25 5 and 6 engaging with contacts 18 and 19 of the switch block, the circuit through the device will be re-established, thereby energizing the electro-magnet which will immediately pull the latch type 30 armature 7 downwardly so that the detent 10 is out of the path of either of the lugs 25 or 26. In the event that the overload is greater than the amperage at which the electro-magnet will function, it will, of course, be understood that 35 the fusible conductor or connector 21 will "blow" and thus fully protect the line in which the device is installed.

In the event that the fusible conductor 21 for the contacts 18 and 19 becomes ruptured or 40 broken, it is possible to readily replace a new switch disk in the cover by simply removing the fastening 24 and reinserting a new disk with a fresh fusible connector. Therefore, the device as a whole need not be discarded but may be 45 readily replaced in serviceable condition by simply renewing the switch disk 20.

Without further description it is thought that the features and advantages of the invention will be readily apparent to those skilled in the art, 50 and it will of course be understood, that changes in the form, proportion and minor details of construction may be resorted to, without departing from the spirit of the invention and scope of the appended claims.

55 I claim:—

1. An electric service line protector including in combination, an armature type latch normally spring biased to latching position, an electro-magnet for actuating the latch, a pair of oppositely located spring terminals, a switch disk overlying the latch and having means for engaging therewith, said switch disk having opposite contacts connected by a fusible conductor adapted to carry an amperage substantially higher 65 than the amperage for which the electro-magnet is set to function.

2. An electric service line protector including, in combination, a latch spring-biased to latching position, an electro-magnet for the latch, yieldable line terminals mounted to have their free ends to function as pawls, a two-part rotatable cap unit including a cover and a disk rotatably connected and said disk carrying contacts connected by a fusible conductor, said cover and disk being also connected by a coiled tensioning 75

spring, and said disk having means to engage said latch, and ratchet means on said cover for engaging the pawl ends of the line terminals.

3. An electric service line protector including, in combination, a latch spring-biased to latching 5 position, an electro-magnet for the latch, a pair of combined pawl and line terminal elements, a rotatable cover having ratchet shoulders thereon for cooperating with said terminal elements to compel movement of the cover in one direction, a disk, conductor means on the disk for bridging said line terminals, a coil spring for connecting the disk to the cover, said disk having means cooperating with the cover to limit its movement relative thereto, and means on the 10 disk for engaging the latch to tension the coil spring when the ratchet shoulders on the cover are in abutting engagement with the combined terminal and pawl elements, thereby to cause the conductor means on the disk to complete a 15 circuit between the line terminal elements.

4. An electric service line protector including, in combination, a base having spring line-terminal members, a latch spring-biased to latching 25 position, an electro-magnet for said latch, a rotatable cover having ratchet shoulders cooperating with the ends of said terminal members to compel movement of the cover in one direction, a disk within the cover and having contacts bridged by a conductor, a coil spring for connecting the disk with the cover, and means on the disk for engaging with the latch for tensioning the disk relative to the cover and also normally to maintain the contacts on the disk 30 in engagement with the terminal members. 35

5. An electric service line protector including, in combination, an electro-magnet, a pair of spring brush terminals, one of which is included in circuit with said electro-magnet, a spring-biased armature-type latch responsive to a field 40 generated by the electro-magnet, a rotatable cover having abutments thereon, a switch disk mounted on the cover and movable between said abutments, a spring connecting the disk and cover, means on the disk for engaging said latch, 45 a pair of contacts on the switch disk for engaging said terminals, and a fusible conductor connecting said contacts.

6. An electric service line protector comprising, in combination, a base, an electro-magnetic 50 latch thereon, upstanding brush terminals on the base, a cover rotatably held to the base, insulating barrier walls carried by the inside face of the cover and projecting therefrom into the zone of the upstanding brush terminals, said 55 walls being spaced from each other at their ends, and one adjacent pair of ends being notched to provide abutment shoulders, a switch disk housed within the said walls, a radial arm on the disk for alternately engaging with said shoulders, a coil spring for connecting the disk to the cover, 60 and contacts carried by the disk and connected by a fusible conductor.

7. An electric service line protector comprising, in combination, a base of insulating material, an electro-magnetic latch on the base 65 spring-biased to normal position, line terminals at opposite sides of the base and comprising upstanding spring members with free end portions, an insulating cover rotatably held to the 70 base, arcuate insulation walls on the cover at the inside faces of the line terminals spaced apart at their ends to provide clearances for the free end portions of the line terminals to spring inwardly and the rear ends of said walls adapted to 75

engage the free end portions of said terminals, a disk having a central chamber for receiving a coil spring, one end of which is connected to the disk while the other is anchored to the cover, contacts on the disk at diametrically opposite points and connected by a conductor, cooperating means on the disk and insulation walls to limit movement of the disk relative to the cover, and diametrically spaced means at the face of the disk opposite the cover for alternately engaging with said latch means.

8. An electric service line protector comprising, in combination, a base of insulating material, an electro-magnetic latch on the base spring-biased to normal position, line terminals at opposite sides of the base and comprising upstanding spring members with free ends, an insulating cover rotatably held to the base, arcuate insulation walls on the cover at the inside

faces of the line terminals, each wall having a pointed toe and a shouldered heel and spaced apart circumferentially to provide clearances for permitting the free end portions of the terminal springs to move inwardly, a disk having opposite contacts connected by a conductor adapted to be normally exposed in said clearances to engage the terminals springs, said disk being mounted on the cover within the arcuate members and connected by a coil spring with the cover, a radial projection on the disk movable between spaced abutments on the arcuate insulation walls, and means at the face of the disk lying next to the latch for engaging the latter to cause the spring to be fully tensioned when the shouldered heel portions of the insulation walls are engaged with the ends of the line terminals. 5 10

JOSEPH E. FARRELL.
